UNITED STATES PATENT OFFICE

KARL KISSENDORFER, OF OBERNDORF-ON-THE-NECKAR, GERMANY, ASSIGNOR TO
MAUSER-WERKE AKTIENGESELLSCHAFT, OF OBERNDORF-ON-THE-NECKAR, GERMANY

CALIPER

Application filed July 7, 1928, Serial No. 291,063, and in Germany July 30, 1927.

My invention relates to calipers and more particularly to a caliper of the type disclosed in the German patent specification No. 408974 and comprising a pair of similar bars having at their extremities jaws and interconnected by a dovetailed guiding member which in the patent referred to is slotted lengthwise for the purpose of resiliency.

The object of my invention is to provide a caliper of this nature which will include improved means adapted to act or operate in a most reliable way with a view to ensure delicate adjustments and a smooth sliding of the two bars on and in contact with each other while being adjusted so as to eliminate as far as possible the chance of failure and increase the efficiency of the device.

With the above recited object in view reference is made to the following specification and annexed drawings in which there is exhibited one example or embodiment of the invention which, however, is in no way intended as a limitation upon the scope of the appended claims as it is to be clearly understood that variations and modifications which fairly fall within the true scope of said claims may be resorted to when found expedient, the invention viewed from its broadest aspect residing in the guiding member being a bipartite structure composed of a guiding bar properly speaking and a braking bar cooperating therewith as will be described more in detail in the following specification.

In the accompanying drawings forming a part of this specification and wherein like reference symbols designate like parts throughout the several views:

Figure 1 is a view in side elevation of a caliper constructed in accordance with the present invention; Figure 2 is a view in cross-section taken on the line A—B of Figure 1; Figure 3 is a similar view on an enlarged scale and with certain parts cut away, the illustrated parts showing in a more conspicuous manner the construction, arrangement and cooperation of the two bars constituting the bipartite structure hereinbefore referred to; Figure 4 is a view in side elevation and in vertical cross-section of the

guiding bar; and Figure 5 is a similar view of the braking bar.

In the embodiment shown *m* and *n* designate the two main or measuring bars, respectively, each provided with a jaw. The inside faces of the two bars *m* and *n* are recessed lengthwise to form dovetail-grooves in which a guiding bar *a* and a braking bar *b* are encased in the particular manner clearly shown in Figure 3, so as to constitute the means for holding the bars *m* and *n* in assembled position but free for adjusting displacement.

The guiding bar *a* is firmly connected with the main bar *n* and comprises a dovetail-portion *a*¹ of greater width exactly corresponding to the width of the groove of the bar *n*, and a dovetail-portion *a*² being integral with each other so as to constitute a double dovetail-bar as shown.

The dovetail-groove of the main bar *m* is of the same width or cross-sectional area as that of the main bar *n* and the dovetail portion *a*² of the guiding bar *a* is housed in the groove of the main bar *m*. The braking bar *b* is of less width than the guiding bar *a* by the width of the portion *a*² of the latter or, in other words the difference in width of the two bars *a* and *b* is equal or amounts to the width of the portion *a*² of the guiding bar *a*, so that, as the brake bar *b* is of parallelopipedic cross-section corresponding, in angular respects, to the dovetail configuration or contour of the bar *a*, the bar *b* and the portion *a*², supplement each other in filling out the dovetail-groove of the main bar *m*, as will be readily understood on inspection of Figure 3.

It will be seen that the upper oblique side face of the brake-bar *b*, see Figure 3, engages the upper slanting surface of the groove of the main bar *m*, while the lower oblique side face of the bar *b* which is in parallel relationship to the former, engages the counterface of the portion *a*² of the guiding bar *a*, when the parts are duly assembled. For the purpose of clamping the bars in any desired or adjusted position I employ conventional screw-bolts *c*¹ acting to fix the main bar *m* in the usual manner so that a more detailed de-

scription of the fixing means is deemed unnecessary.

It is to be noted, however, that the required resilient co-operation of the parts will be realized in the embodiment shown by the provision of yielding washers *d* on the stem of the screw-bolt *c*. The latter are adapted to pass freely through openings of the main bar *n* and the bar *a* with their heads substantially flush with the outer surface of the bar *n*, and to engage in threaded bores or holes of the brake bar *b*. In the event that the screw-bolts slacken the two main bars *m* and *n* still will be maintained in firm connection with each other due to the resilient pressure of the washers and when the screw-bolts are unserved and the main bars or jaws are free to be displaced in any desired position, such displacement can be accomplished in a thoroughly smooth manner.

In view of the foregoing a detailed description of the operation of the device is deemed unnecessary and is therefore omitted in the interest of brevity. Nor does it seem necessary to burden this specification with an exposition of the advantages which the invention possesses, for they will be apparent to those skilled in the art to which this invention pertains.

What I claim is:—

1. A caliper of the type referred to, comprising two laterally co-operating main bars having jaws at their outer ends and a longitudinal groove in each of the two co-operating surfaces of the bars, a guiding bar in the groove of one main bar, a brake bar in the groove of the other main bar, and means carried by the brake bar for releasably and adjustably interconnecting the bars.

2. A caliper of the type referred to, comprising two laterally co-operating main bars having jaws at their extremities and a longitudinal groove in each of the two co-operating surfaces of the bars, a stationary guiding bar in the groove of one main bar, an extension of the said stationary bar engaging in the groove of the other main bar, a brake-bar mounted in the groove of said other main bar, and means carried by the brake bar for releasably and adjustably interconnecting the bars together.

3. A caliper of the type referred to, comprising two laterally co-operating main bars having jaws at their extremities and a longitudinal dovetail groove in each of the two co-operating surfaces of the bars, a correspondingly dovetailed, stationary guiding bar in the groove of one main bar, a dovetailed extension of the said stationary bar engaging in the groove of the other main bar, a brake-bar of dovetail cross-section also mounted in the groove of said other main bar with its one end face abutting against one lateral face of the groove and with its other end face engaging against the said extension, and means

carried by the brake bar for releasably and adjustably interconnecting the bars together.

4. In a caliper of the character set forth, including two laterally co-operating main bars provided with grooves and jaws at their extremities, the dovetailed interconnecting structure composed of two single members in the grooves, the one of double-dovetail cross-section and the other one of parallelopipedic cross-section and means for adjusting the bars.

In testimony whereof I affix my signature.

KARL KISSENDORFER.
